DISPENSING JUG

Carl C. Conkle, Tarzana, Calif., assignor to Solar Systems, Inc., North Hollywood, Calif., a corporation of Delaware

Filed Mar. 19, 1962, Ser. No. 69,322

Term of patent 7 years

(Cl. D58—17)

FIG. 1 is a perspective view of a dispensing jug showing my new design;

FIG. 2 is a side elevational view thereof;

FIG. 3 is a top plan view thereof;

FIG. 4 is a bottom plan view thereof;

FIG. 5 is an enlarged fragmentary sectional view taken on line 5—5 of FIG. 2; and

FIG. 6 is an enlarged fragmentary sectional view taken on line 6—6 of FIG. 5.

I claim:

The ornamental design for a dispensing jug, substantially as shown.
